CLAIM

The ornamental design for an automotive oil catch can as shown and described.

DESCRIPTION

FIG. 1 is a top front perspective view of the automotive oil catch can according to the present application;

FIG. 2 is a top back perspective view of FIG. 1;

FIG. 3 is a front view of FIG. 1;

FIG. 4 is a back view of FIG. 1;

FIG. 5 is a top view of FIG. 1;

FIG. 6 is a bottom view of FIG. 1;

FIG. 7 is a side view of FIG. 1; and,

FIG. 8 is a side view of FIG. 1.

The broken line showing is included for the purpose of illustrating unclaimed subject matter and forms no part of the claimed design.

1 Claim, 8 Drawing Sheets
